UNITED STATES PATENT OFFICE

135,296

DESIGN FOR A DESSERT JAR

Lawrence R. Sereno, Montreal, Wis.

Application November 9, 1942, Serial No. 108,731

Term of patent 3½ years

To all whom it may concern:

Be it known that I, Lawrence R. Sereno, a citizen of the United States, residing at Montreal, in the county of Iron and State of Wisconsin, have invented a new, original, and ornamental Design for a Dessert Jar, of which the following is a specification, reference being had to the accompanying drawing, forming part thereof.

Fig. 1 is a front elevational view of a dessert jar showing my new design;

Fig. 2 is a side elevational view;
Fig. 3 is a top plan view; and
Fig. 4 is a sectional view on line 4—4 of Fig. 1 looking in the direction of the arrows.

I claim:

The ornamental design for a dessert jar, as shown.

LAWRENCE R. SERENO.
